Attn:

UNITED STATES PATENT OFFICE.

WILLIAM KIRKWOOD, OF GUELPH, ONTARIO, CANADA.

RADIATOR.

SPECIFICATION forming part of Letters Patent No. 313,082, dated March 3, 1885.

Application filed October 16, 1884. (No model.) Patented in Canada October 24, 1884, No. 20,422.

To all whom it may concern:

Be it known that I, WILLIAM KIRKWOOD, of the city of Guelph, in the county of Wellington, in the Province of Ontario, Canada, 5 plumber, have invented certain new and useful Improvements in Radiators; and I do hereby declare that the following is a full, clear, and exact description of the same.

The object of the invention is to design a 10 radiator in which either hot water or steam may be used, and in which the heating-surface is so arranged that not only is heat secured by radiation from the outer jacket of the radiator, but also from its interior, which is de- 15 signed to act as a hot-air heater; and it consists in the peculiar combination and the construction and arrangement of parts hereinafter more fully described and claimed.

The drawing represents two sections of my 20 improved radiator, one section being shown in section to exhibit its interior construction, while the outside of the other is exposed.

A represents a tube open at both ends, and 25 preferably supported by the hollow base-plate B, which should be scalloped at its bottom or perforated, in order to fully admit fresh air, which will circulate through the tube A when it becomes heated. This tube A is placed within the jacket or larger tube C. The collar a, placed at each end of the tube A, fills 30 the space between the outer jacket, C, and the inner tube, A. These collars a, it will be noticed, are a short distance from each end of the tubes. This outer space is filled up with 35 any suitable cement, so as to form a steam-tight joint at each end of the space formed between the tube A and the outer casing, C. An annular enlargement, b, is formed at each 40 end of the jacket C, at the point where the supply or connecting pipes D are attached to the said jacket, so that where the steam or water enters the jacket a larger space is provided, to enable it to freely circulate around the inner pipe, A, immediately upon its entrance. This annular enlargement b is important for the satisfactory working of my improved radiator, as the circulation around the spaces between the two tubes is thereby greatly improved.

50 It will be seen that as many tubes A C as

desired may be arranged in connection with each other, as indicated, to constitute as large or as small a radiator as will be required.

B' is a flaring cap placed over the top of the tube C, as shown, and is designed to receive 55 a slab or covering, as desired. This cap is scalloped to form outlets for the heated air from the pipe A, as will be readily understood.

It will also be seen from this description that the hot water or steam admitted through the 60 pipes D will not only heat the room by radiation from the sides of the jacket C, but will also heat the air passing through the inner tube, A, so that each tube becomes a hot-air 65 heater, by which arrangement I not only se- 70 cure all the advantages of an ordinary steam or hot-water radiator, but also obtain the benefits of a series of hot-air flues. Conse- 75 quently I obtain the benefit of a hot-air heating-surface as well as a hot-water or steam one. 70

I also attach importance to the flaring cap B' having air-outlets, for by its use a slab or covering can be placed over the top of the tubes, so as to completely cover the same and prevent dirt, &c., falling therein, and yet al- 75 low the heated air to escape into the room.

I am aware that an air tube provided with shoulders arranged within a steam-tube and having a cemented joint has heretofore been proposed.

I am also aware that the outer or steam tube has been provided with enlargements, and I therefore do not claim such, broadly.

I am also aware of the Patent No. 227,517, and make no claim to the construction shown 85 therein as forming part of my invention.

What I claim as my invention is—

1. The continuous hollow base-plate B, pro- 90 vided with air-inlets above its bottom, the outer tubes, C, supported and connected by said base-plate, and provided with enlargements b, and the inner tubes, A, suspended concentrically within said tubes C, said inner tubes, A, being formed independent of each other, and the supply or connecting pipes D 95 connecting the outer tubes at their enlargements, substantially as and for the purpose specified.

2. The hollow perforated base-plate B, the outer tube, C, supported thereby, the tube A, 100

placed within said tube, and having collars *a*, said tube *C* having annular enlargement *b*, and provided with a flaring cap, *B'*, having air-outlets *b'*, in combination with a slab or covering, and the supply-pipes *D*, substantially as and for the purpose specified.

3. In combination with the perforated base-plate *B*, the flaring cap *B'*, and a slab or covering supported by said cap, the tube *C*, supported by said base-plate, and the tube *A*,

placed within said tube *C*, and provided with collars *a*, the space between the collars and the outer end of the pipes being filled with a cement, substantially as and for the purposes specified.

Toronto, September 27, 1884.

WILLIAM KIRKWOOD.

In presence of—

CHARLES C. BALDWIN,

JAS. E. MAYBEE.
